PREPARATION OF AMMONIUM SULPHATE

Robert R. Fulton, Pittsburgh, Pa., assignor to
The Koppers Company of Delaware, a corpora-
tion of Delaware

Application September 5, 1931, Serial No. 561,415

5 Claims. (Cl. 23—119)

This invention relates to processes of preparing ammonium sulphate.

An object of the present invention is to provide a process of preparing ammonium sulphate by the oxidation of ammonium sulphite. Another object is to provide improvements in methods of oxidizing ammonium sulphite so as to make feasible the efficient production of ammonium sulphate therefrom on a commercial scale.

I have found in the manufacture of ammonium sulphate by the oxidation of ammonium sulphite, particularly when the latter is in solution, that when the oxidizing gas is finely dispersed substantially throughout the body of the solution treated, increased yields of ammonium sulphate are obtained. It is particularly advantageous to have the gas in a finely divided state at the place at which the gas is introduced into the solution. Oxidizing gas is preferably introduced at the base of a relatively tall column of the liquid containing ammonium sulphite for the purpose of taking advantage of the hydrostatic pressure. This increased pressure at the base combined with the introduction of oxidizing gas in extremely finely divided condition in a region at the base of the column brings about rapid oxidation of the ammonium sulphite. The column is preferably of such a height that substantially no union of the gas bubbles occurs in the upper regions of the column.

Good results are obtained by treating an alkaline solution of sulphite, but the present process operates more efficiently when the sulphite solution is in neutral or preferably in acid condition while contacting with an oxidizing gas. The preferred pH value is from about 5.5 to 7.0. Ammonia-containing gases or sulphur dioxide-containing gases may be passed into the sulphite solution intermittently or continuously either to vary the hydrogen ion concentration or to maintain it constant.

Other features of the present invention will be set forth in a further description of the process which may be carried out in apparatus such as that shown by way of example in the accompanying drawings, in which,

Figure 1 is a vertical sectional view partly in elevation of one form of apparatus, and

Fig. 2 is an elevational view, partly in cross section of another form of apparatus.

In the apparatus shown in Fig. 1, a solution containing ammonium sulphite is passed into a tall narrow column 1 through a pipe 2 controlled by a valve 2' near the base of the column or into

the top through a pipe 3 controlled by a valve 3'. Columns from six feet to about sixty feet in height and up to ten feet or more in width are employed.

The column is filled to any desired level with 5 solution containing ammonium sulphite.

An oxidizing gas such as air, ionized air, oxygen, or gases containing oxygen or ozone are passed through a porous plate 4 at the base of the column 1. The oxidizing gas is introduced beneath the plate 4 through a pipe 5 controlled by 10 a valve 6.

The plate 4 may be of any fine porous material which will produce fine bubbles in the sulphite solution and which will permit the passage of the 15 gas at a fairly rapid rate. The bubbles are represented in the drawing by small circles. Plates made of fritted glass or the fine grades of aluminum plates are suitable. The rate of passage of the gas must be kept below that at which the 20 gas tends to lift the solution bodily out of the column; but the rate is high enough to keep the solution in a foaming state. A meter 7 is provided for measuring gas.

The pressure employed for forcing the oxidizing gas through the porous plate and the column 25 of solution, depends upon the fineness of the pores in the plate and upon the height of the column.

Means are provided for recirculating gas or 30 solution or both through the column 1. During the passage of gas into the solution, the latter passes out near the top of the column, downwardly through a pipe 8 and back into the bottom of the column through the turned-up end 9 of 35 the pipe 8.

The gas passing upwardly through the solution, collects in a chamber 10 at the top of the column 1 and is withdrawn either through a pipe 11 controlled by a valve 12, or by closing the 40 valve 12 the gas is passed into a pipe 13 controlled by a valve 14 and by means of a pump 15 is forced into the pipe 5 and through the plate 4 into the solution in the column 1.

The alkalinity or acidity of the ammonium 45 sulphite solution in the column may be controlled by admitting ammonia-containing gas or sulphur dioxide-containing gas into the solution. These gases are preferably passed into the solution through the plate 4 in which case they are 50 admitted separately into the pipe 5. To prevent deposition of solid ammonium salt, after ammonia has been fed into the pipe 5 through a pipe 17 for instance, controlled by a valve 18, the ammonia gas is swept through the plate 4 55

by the oxidizing gas before admitting sulphur dioxide gas through a pipe 19 controlled by a valve 20, and sulphur dioxide is swept out before ammonia is admitted.

5 The ammonia-containing gas or the sulphur dioxide-containing gas may be, if desired, passed through the porous plate along with the stream of oxidizing gas either intermittently or continuously. By the proper regulation of the 10 valves, the proportions of the gases may be controlled.

The gases before leaving the top of the column 1, and particularly if they are withdrawn through the pipe 11, may be sprayed by means 15 of a spray 21 controlled by a valve 22, with ammonia solution or with acid sulphite solution or dilute sulphuric acid depending on the sulphur dioxide or ammonia content of the gases.

The temperature of the solution in the column, if desired, is controlled by any suitable means. If the temperature used is above atmospheric, a heating jacket 23, for instance, is used. Steam or other heating fluid is admitted through a pipe 24 controlled by a valve 25 and withdrawn 25 through a pipe 26 controlled by a valve 27. A pipe 28 controlled by a valve 29 may be provided for withdrawal of condensates. The heating fluid may be substituted by a cooling fluid if necessary. A thermometer 30 is provided for determining 30 the temperature of the solution in the column 1.

Good results are obtained by maintaining a temperature during oxidation of substantially 30° C. to 45° C. Temperatures as high as 60° C. or even 80° C. may be employed. When conducting the oxidation under superatmospheric pressure, the temperatures may even be higher than those mentioned.

The temperature of the solution in the column may also be controlled by withdrawing heated 40 solution through a pipe 31 controlled by a valve 32 and by passing in solution of lower temperature through the pipe 2 or the pipe 3 or through both. The concentration of the solution in the column may also be controlled in this way.

45 Solutions containing various proportions of ammonium sulphite or ammonium bisulphite or both may be treated. Solutions containing substantially 10% to 20% ammonium sulphite give satisfactory yields of ammonium sulphate. However a highly satisfactory method is to treat 50 solutions at such temperatures that when cooled to lower temperatures a supersaturated solution of ammonium sulphate forms and crystals of this salt readily separate out.

55 In the latter case the solution is withdrawn from time to time through the pipe 31 and passed into a drain table 33 to permit settling out of crystals of ammonium sulphate. The solid ammonium sulphate 34 with adhering mother liquor is passed into a centrifuge 35 and the dried ammonium sulphate is then ready for shipment.

The mother liquor from the drain table 33 drains out through a pipe 36 and is joined in 60 a tank 37 with liquor coming from the centrifuge 35 through a pipe 38. The mother liquor in the tank 37 is pumped by means of a pump 39 through a pipe 40 into the top of the column 1.

It has been found that the presence of ammonium sulphate in the sulphite solution is highly beneficial and aids in the more rapid and complete oxidation of the sulphite. A sulphite solution containing up to about 35% and preferably not more than substantially 40% ammonium sulphite gives satisfactory results. By main-

taining the concentration of ammonium sulphate high enough, the solution and gases may be recirculated in the column 1 until crystals of ammonium sulphate form and the resulting slurry may be withdrawn from the column and passed to the drain table 33 where the solid ammonium sulphate is separated.

Under increased pressures the oxidation may be speeded up and higher yields of ammonium sulphate are obtained. Although the present process may be carried on at any pressure, particularly at atmospheric pressure and above, it is preferable to increase the pressure in the later stages of the conversion. The last traces of ammonium sulphite are difficult to convert to sulphate but by increasing the pressure, 100 per cent conversion is obtained. Alternatively, the addition of a small amount of sulphuric acid, serves to change traces of sulphite to sulphate.

In the apparatus shown in Fig. 1, the pressure in the column 1 is built up by closing the valve 12 in the pipe 11, forcing oxidizing gas into the column through the pipe 5 until the desired pressure is reached, and then closing the valve 6. The valve 14 in the pipe 13 is opened and the gas 20 is repeatedly circulated through the solution by means of the pump 15.

Pressures in the lower regions and at the bottom of the column may be raised or lowered by varying the height of the column of solution 25 treated. The column 1 may be filled to a relatively low level at the beginning of the process and after the reaction has proceeded for a time, the level may be raised by the addition of fresh sulphite solution or previously aerated solution. 30 For instance, in some cases a saturated solution of ammonium sulphate may be added or a solution of substantially the same composition as that which is being treated in the column, may be added.

A trough 41 is provided to catch any liquid which flows over the top of the column 1 and the overflow is drawn off through a seal 42.

The sulphur dioxide used in the present process 45 may be derived from various sources as for instance by roasting metallic sulphides, or by burning sulphur or hydrogen sulphide.

The ammonia may be synthetic ammonia, or ammonia obtained by treating ammonium compounds with alkali or alkaline earth hydroxides, 50 or it may be obtained from ammonia liquor obtained in the treatment of coal gases.

Crude ammonia liquors from coal gas plants contain besides ammonium hydroxide, varying amounts of sulphides, and cyanides as well as 55 organic materials such as pyridine, tar acid oils, naphthalene and other compounds. When treating ammonia liquors, it is highly advantageous to remove the oily materials present therein. These materials tend to retard the oxidation 60 reaction. They rise to the surface and may be removed from the liquid in the column 1 by permitting them to overflow into the trough 41.

Also, when treating ammonia liquors, it is advantageous to add sulphur dioxide in excess of the amount required to neutralize the ammonia and other alkaline substances, in order to decompose the sulphides and cyanides, which are driven off later as hydrogen sulphide and hydrogen cyanide. If the sulphite liquor is left 70 alkaline, the sulphides and cyanides form thioulate and thiocyanate which are undesirable impurities in ammonium sulphate. Furthermore when the liquor is acid, the effect of pyridine is eliminated since it is converted to 75

a salt which dissolves in the sulphite liquor. Also, dispersion of the oxidizing gas is best in an acid medium.

The presence of certain impurities in aqua ammonia, such as primary amines, causes the formation of formaldehyde in the very last stages of the oxidation period. The detection of the first traces of formaldehyde serves as an indication of practically the end of the oxidation period and for some purposes the oxidation may be stopped at this time.

In the apparatus shown in Fig. 2 a series arrangement of columns is shown. Although only two columns 45 and 46 are shown, any number 15 may be used. The columns shown are constructed similarly to the column shown in Fig. 1 and are provided with heating jackets 47 and 48, and porous plates 49 and 50 at their respective bases.

20 Solution to be treated is passed into the column 45 through a pipe 51 controlled by a valve 52. The solution is withdrawn from the bottom of the column and by means of a pump 53 is pumped into the top through a pipe 54. This 25 recirculation may be kept up until any desired stage of oxidation has been reached and then passed into the top of the column 46 through a pipe 55 for further treatment. By proper manipulation of the valves 56 and 57 the liquid 30 stream passing through the pipe 54 may be divided in any ratio.

The liquid may be maintained at a higher 35 temperature in the column 46 than the liquid in the column 45 and may be recirculated by pumping it from the bottom to the top by means of a pump 58 through a pipe 59. It may be noted here that the oxidizing gas and sulphite 40 solution travel countercurrently in the towers shown in Fig. 2 and concurrently in the tower 45 shown in Fig. 1.

The oxidizing gas is passed into the bottom 50 of the column 46 through a pipe 60 controlled by a valve 61, out of the top of the column 46 and into the bottom of the column 45 through 55 a pipe 62. By proper control, if air is used as the oxidizing gas, the gas leaving the top of the column 45 through a pipe 63 provided with a valve 64, is substantially all nitrogen.

Pipes 65 and 66 provided respectively with 60 valves 67 and 68, respectively conduct ammonia-containing gas and sulphur dioxide-containing gas into the pipe 60. Pipes 69 and 70 provided respectively with valves 71 and 72, respectively conduct ammonia-containing gas and sulphur 65 dioxide-containing gas into the pipe 62.

Treated solution containing ammonium sulphate is withdrawn from the top of the column 46 through a pipe 73 controlled by a valve 74 and passed into an evaporator 75 provided with 70 the usual heating means 76. Solution may also be passed from the bottom of the column to the evaporator through the pipe 59, through a pipe 77 provided with a valve 78, and then through a part of the pipe 73.

65 The slurry formed in the evaporator 75 is withdrawn through a pipe 79 by opening a valve 80 and is passed to a centrifuge 81 from which practically dry ammonium sulphate 82 is obtained.

70 Various modifications may be made in the process and apparatus described and various types of apparatus may be employed in the present process. As a means for distributing the oxidizing gas in the sulphite solution, propellers 75 may be mounted for rotation in the bottom of

the column of solution above a gas inlet. By rotating the propeller the gas is beaten into the solution.

Another means for injecting oxidizing gas into the sulphite solution is a perforated pipe. However, since it is important to produce a uniform mixture of finely divided gas and solution, perforated plates are preferred and are employed as shown in the drawings. Minute bubbles are thereby distributed over a large area at the base 10 of the column.

Instead of providing indirect heating means for the columns as shown, heated oxidizing gas 15 may be injected into the solution, whereby direct heating is accomplished. If the temperature of the solution rises above any desired point, cooled gases may be injected to lower the temperature.

To carry on the present process under pressure throughout the oxidation stage or during any portion thereof, the sulphite-containing solution 20 may be placed in autoclaves provided with an inlet and outlet for oxidizing gas. The gas may be admitted until a desired superatmospheric pressure is reached after which the autoclave 25 may be sealed and the mixture of gas and solution agitated by means of paddles or by rotation of the autoclave.

If desired, the oxidation of the ammonium sulphite may be carried on in the presence of a catalyst. The catalysts may be gaseous, liquid 30 or solid substances.

The addition of foaming agents to the sulphite solution greatly improves dispersion of the oxidizing gas. The addition of as little as two 35 grams of licorice root extract or saponin in twenty-five gallons of solution is very effective.

I claim as my invention:

1. A process of preparing ammonium sulphate, which comprises introducing an oxidizing gas 40 into a solution containing ammonium sulphite in a closed chamber and thereby building up pressure therein and thereby converting a major portion of the sulphite to sulphate, and thereafter discontinuing the introduction of oxidizing gas and converting the remainder of the sulphite 45 to sulphate by recirculating the gas contained therein under the so built-up pressure through the solution.

2. A process of preparing ammonium sulphate, which comprises introducing an oxidizing gas 50 in finely divided condition into a solution containing ammonium sulphite and thereby converting a major portion of the sulphite to sulphate, increasing the pressure in the later stages of conversion and thereby continuing conversion as aforesaid and 55 thereby converting the remainder under such increased pressure.

3. A process of preparing ammonium sulphate, which comprises introducing an oxidizing gas 60 in finely divided condition into the bottom of a column of liquid containing ammonium sulphite and thereby converting a major portion of sulphite to sulphate, and adding a small amount of sulphuric acid to the column during the introduction of the oxidizing gas to change last traces 65 of sulphite to sulphate.

4. A process of preparing ammonium sulphate, which comprises introducing an oxidizing gas 70 into liquid containing ammonium sulphite and ammonium sulphate in a finely divided condition at the place at which the gas is introduced into the liquid and thereby converting the ammonium sulphite to ammonium sulphate, and maintaining the proportion of ammonium sulphate in the liquid from about 30% to 40% during the conversion, 75

and maintaining the height of the hydrostatic head of such height that substantially no union of gas bubbles occurs in the upper regions of the hydrostatic column.

5. A process of preparing ammonium sulphate, which comprises introducing an oxidizing gas into a solution under pressure and containing ammonium sulphite and thereby converting the ma-

5 jor portion of the sulphite to sulphate, and thereafter discontinuing the introduction of oxidizing gas and converting the remainder of the sulphite to sulphate by recirculating the gas contained therein through the solution under increased pressure.

ROBERT R. FULTON.
